UNITED STATES PATENT OFFICE.

ALFRED THEADORE PETERSON, OF FERNIE, BRITISH COLUMBIA, CANADA, ASSIGNOR
OF ONE-HALF TO ERIC VICTOR PARSON, OF FERNIE, BRITISH COLUMBIA, CANADA.

LACE-HOOK FOR BOOTS AND SHOES.

1,126,852.

Specification of Letters Patent.

Patented Feb. 2, 1915.

Application filed December 9, 1913. Serial No. 805,635.

To all whom it may concern:

Be it known that I, ALFRED THEADORE PETERSON, of the village of Fernie, in the district of East Kootenay, in the Province 5 of British Columbia, Canada, have invented certain new and useful Improvements in Lace-Hooks for Boots and Shoes, of which the following is the specification.

My invention relates to improvements in lace hooks for boots and shoes and the object 10 of the invention is to provide a simple means for closing the mouth of the hook automatically by the engagement of the lace with the hook and thereby prevent catching of the 15 hook end in the garments or other obstruction and it consists essentially of a lace hook having side lugs formed in the hook end and an internal groove extending from the base of the lugs to the base of the hook having 20 the lower portion thereof concentric with the center of the lugs, a closing member designed to extend across the mouth of the hook provided with a tail piece pivoted between the lugs and fittings into the groove 25 when in the closed position and a spring for throwing the tail piece outwardly toward the mouth of the hook as hereinafter more particularly explained by the following 30 specification.

Figure 1, is a front elevation of a shoe top showing my hook applied to the shoe and the shoe to the wearer. Fig. 2, is an enlarged perspective detail of my hook attached to a shoe portion. Fig. 3, shows the 35 parts separated. Fig. 4, is a side elevation showing the hook in the closed position. Fig. 5, is a side elevation showing the hook in the open position. Fig. 6, is a vertical section through Fig. 4. Fig. 7, is a sectional 40 view on line $x-y$ Fig. 5.

In the drawings like letters of reference indicate corresponding parts in each figure.

A is the body of my hook preferably cast and provided with a flattened bottom portion A' fitting against the shoe upper and from which the stem A² extends through the shoe upper.

A³ is a washer extending around the stem, the end of the stem being riveted over the 45 washer to secure the hook in position. The hook end A⁴ of the body is divided to form spring lugs A⁵ having inwardly extending opposing teats A⁸.

A⁶ is a portion extending up from the base

of the body so as to form the opposite side 55 of the mouth of the hook.

B is a hook closure comprising a broad portion B' designed to extend when in the closed position from the lugs A⁵ forming one side of the hook mouth to the portion A⁶ 60 forming the other side of the hook mouth.

B² is a tail piece extending from the piece B' and having recesses on its opposite side into which the teats A⁸ fit to form a pivot.

A⁷ is a groove extending from the base of 65 the lugs A⁵ and formed concentric with the curve of the hook for the major part, the lower portion being concentric with the center of the teats A⁸.

C is a spring preferably cast in the tail 70 piece B² so as to project outwardly therefrom and bear against the base of the groove A⁷, the tendency of the spring being always to force the tail piece B² outwardly at its lower end toward the portion A⁶, and the 75 closing piece B' upwardly until the end thereof shoulders against the lugs A⁵.

In tying the shoe the lace is passed into the mouth of the hook in the usual manner and beneath the end of the closure B' 80 against the tail piece B². When the lace is tightened up the tail piece B² is drawn into the groove A⁷ against the spring C and into the position shown particularly in Fig. 3. By this means it will be seen that the face 85 of the hook will present a smooth rounded surface which will absolutely prevent any portion of the garment or other article catching therein and will at the same time provide a hook which will be strong, durable 90 and neat in construction.

What I claim as my invention is.

A lace hook for boots and shoes comprising a hook body having lugs formed at one side of the mouth of the hook, and a groove 95 extending from the base of the lugs around the interior of the hook, a hook closure pivoted between the lugs, a curved tail piece forming an inward extension of the closure, resilient means located between the tail piece 100 and the base of the groove and secured to said tail piece, as and for the purpose specified.

ALFRED THEADORE PETERSON.
